US0D1010007S

(12) **United States Design Patent** (10) Patent No.: **US D1,010,007 S**
(45) Date of Patent: ** Jan. 2, 2024

(54) **GAME CONTROLLER**

(71) Applicant: **Valve Corporation**, Bellevue, WA (US)

(72) Inventors: **Carl Samuel Conlee, IV**, Seattle, WA (US); **Philip Bryan**, Bellevue, WA (US); **Claire Gottschalk**, Bellevue, WA (US); **Jeremy Slocum**, Sammamish, WA (US)

(73) Assignee: **VALVE CORPORATION**, Bellevue, WA (US)

(**) Term: **15 Years**

(21) Appl. No.: **29/876,882**

(22) Filed: **May 30, 2023**

Related U.S. Application Data

(62) Division of application No. 29/843,757, filed on Jun. 23, 2022, now Pat. No. Des. 994,778, which is a division of application No. 29/764,718, filed on Dec. 31, 2020, now Pat. No. Des. 960,244, which is a division of application No. 29/648,235, filed on May 18, 2018, now Pat. No. Des. 908,798.

(57) **CLAIM**

The ornamental design for a game controller, as shown and described.

DESCRIPTION

FIG. 1 is a back perspective view of a game controller; FIG. 2 is a front perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

FIGS. 1–8 illustrated a right-hand game controller thereof, the left hand game controller being a mirror image thereof. The broken lines depict portions of the game controller that form no part of the claimed design.

1 Claim, 8 Drawing Sheets
